UNITED STATES PATENT OFFICE.

THOMAS TINSLEY HEATH, OF LOVELAND, AND ALOIS NICHOLAS VERDIN,
OF GLENDALE, OHIO; SAID VERDIN ASSIGNOR TO SAID HEATH.

MULTIPLE PROFILING-MACHINE.

SPECIFICATION forming part of Letters Patent No. 553,988, dated February 4, 1896.

Application filed June 4, 1894. Renewed August 19, 1895. Serial No. 559,807. (No model.)

To all whom it may concern:

Be it known that we, THOMAS TINSLEY HEATH, of Loveland, Clermont county, and ALOIS NICHOLAS VERDIN, of Glendale, Hamilton county, Ohio, have invented certain new and useful Improvements in Multiple Profiling - Machines, of which the following is a specification.

This invention pertains to machines designed primarily for the cutting of metal type or die-sinker punches, but is useful for other work of a similar character.

Our improvements will be readily understood from the following description, taken in connection with the accompanying drawings, in which—

Figure 1 is a side elevation of a machine exemplifying our invention, portions appearing in vertical longitudinal section; Fig. 2, an end elevation of the same, corresponding with the left-hand end of Fig. 1; Fig. 3, a plan of the machine; Fig. 4, a vertical transverse section of the machine, showing the guide employed when a flat groundwork is to be produced; and Fig. 5, a plan and horizontal section of portions of the machine, showing the guides for securing flat groundwork.

In the drawings, ignoring Figs. 4 and 5 entirely for the present, 1 indicates a long horizontal bed; 2, a series of universal bearings mounted thereon in a line at right angles to the length of the bed and in a common horizontal plane; 3, a rod universally journaled in each of these bearings, the rods projecting a short distance to the front and a much greater distance to the rear of their bearings; 4, a blank-holding chuck on the front end of each of the rods 3, these chucks being adapted to receive the blanks on which the letter-cutting is to be done; 5, the blanks held in these chucks and presenting to the left the ends on which the letter-cutting is to be done; 6, a tailward prolongation of one of the rods 3, this prolonged rod being preferably adjustable in length; 7, a bar pivoted to the tail end of all of the rods 3 and equal distances from the universal bearings 2, the distance between the pivots which unite bar 7 to the rods 3 corresponding with the distance between the center of the universal bearings 2, so that a parallel coincident movement is pro-

duced upon all the bars if any one be rocked in any way in its universal bearing; 8, a tail-stock secured to the bed beyond the tail end of the rod 6; 9, a templet-holding chuck upon the tail end of rod 6, this chuck being adapted to receive a contour templet corresponding, but on a much enlarged scale, with the letter to be cut upon the ends of the blanks 5; 10, the templet secured in the chuck 9; 11, a handle on chuck-rod 6, near its tail end, by means of which the rod can be rocked; 12, a guide-pin supported by the tail-stock 8 and having its forward cylindrical end engaging the contour of the templet 10; 13, a head-block mounted to slide horizontally on the head of the bed to and from the chucks 4; 14, a screw mounted on the bed and engaging this head-block and adapted to adjust the head-block to and from the chucks 4, this screw extending tailward to the tail-stock; 15, a pointer and handle on screw 14 at the tail-stock, by means of which the screw may be turned; 16, a graduated dial for indicating the degree of turning which has been given to the screw 14; 17, a series of head-stocks mounted upon the head-block 13 and arranged for sliding motion therein to and from the chucks 4, there being one of these head-stocks for each of the chucks 4 and correspondingly spaced; 18, a cutter-arbor in each head-stock; 19, a cutter in each of the arbors, each presenting its point to the appropriate one of the blanks 5, the axes of the universal bearings 2 being in the lines of the axes of the cutter-arbors, and 20 a screw for each of the head-stocks 17, by means of which those head-stocks can be independently adjusted upon the head-block 13 to and from their chucks 4. Assume the templet 10 to have the form of the letter to be cut upon the blanks, but enlarged ten times over the size of the letter to be cut. Let the length of rod 6 be adjusted, so that as the rod system is oscillated the face of the templet will have a movement ten times as great as that of the faces of the blanks 5. Assume cutters 19 to be square tapering milling-cutters for a cross-dimension adapted to produce the internal angles to be cut in producing the type when the cutters have a given depth of working. Let the end of guide-pin 12 which engages templet 10 have a diameter

equal to ten times that of a working diameter of the cutters at the faces of the blank when working at the given depth. Blanks 5, with their outer ends truly faced, are to be put into 5 the chucks 4, with their faces in a common vertical plane when rod 6 is in a common axial line with guide-pin 12. Screws 20 are then to be adjusted to bring the points of the cutters even with the faces of the blanks. 10 Rod 6 is then to be swung till the blanks clear the cutters sidewise. Screw 14 is then to be turned to draw all the cutters simultaneously toward the blanks a distance equal to the given depth of working. Handle 11 is then 15 to be manipulated to cause the margin of the templet to follow the end of the guide-pin, the result being that the cutters reproduce upon a scale of one-tenth the form of the templet upon the blanks, all of the blanks being 20 cut simultaneously. Handle 15 is then manipulated to withdraw the cutters to a second given depth of cutting, thus appropriately lessening the working diameters of the cutters at the face of the blank, and a second 25 guide-pin 12 is then substituted, the new guide-pin having a working diameter appropriately corresponding with the new working diameter of the cutter at the face of the blank. The templet is again caused to follow the 30 guide-pin, thus producing upon the blanks a further cutting with a cutter of smaller working diameter and better adapted for the keener angles and finer curves of the letter. The cutter is again further withdrawn and a still 35 smaller guide-pin substituted until the work is done. The cut blanks are then removed and their faces polished, which finishes them.

It will be obvious that the groundwork produced by the cutting operation described will 40 be spherical. This is entirely satisfactory for ordinary sizes of printers' type, but for very large sizes a flat ground might be desirable. In such case the guiding arrangement shown in Figs. 4 and 5 may be employed.

The chucks 5 in such case are mounted on a 45 cross-head 23, which slides horizontally in a vertically-sliding cross-head 22, guided in a frame 21, secured to the bed-plate, the universal motion which the chucks are thus capable of making in a true vertical plane being given by chuck-rod 6 through the medium of universal connection 24. The movement of the templet in the previously-described arrangement is also spherical, and for 55 extremely large letter cutting it may sometimes be desirable to cause the templet also to move in a true plane, which may be done by mounting the templet-chuck 9 on a universally-guided cross-head, as in Fig. 5.

60 We claim as our invention—

1. In a profiling-machine, the combination, substantially as set forth, of a universally-

journaled rod, a templet-chuck connected with one end of said rod, a series of blank-chucks connected with the other end of said 65 rod and arranged to receive simultaneous and coincident motion therefrom, a rigidly-supported guide-pin presenting its end to said templet-chuck, a series of cutters presenting their points to said blank-chucks, and means 70 for adjusting the distance between said cutters and blank-chucks.

2. In a profiling-machine, the combination, substantially as set forth, of a universally-journaled chuck-rod, a templet-chuck connected with one end of said rod, a rigidly-supported guide-pin presenting its end to said templet-chuck, a series of blank-chucks connected with the other end of said chuck-rod and adapted to receive simultaneous and coincident motion therefrom, a series of cutters presenting their points to said blank-chucks, means for adjusting said cutters simultaneously toward said blank-chucks, and a screw 80 for each of said cutters for adjusting them independently toward their respective blank-chucks.

3. In a profiling-machine, the combination, substantially as set forth, of a series of universal bearings, a rod journaled in each of 90 said bearings, a blank-chuck upon one end of each of said rods, a bar pivoted to all of said rods and holding them parallel, a chuck-rod in prolongation of one of the previously-mentioned rods, a templet-chuck carried by said 95 prolonged chuck-rod, a rigidly-supported guide-pin presenting itself to said templet-chuck, a series of cutters presenting their points to said blank-chucks, and means for adjusting the distance between said cutters 100 and blank-chucks.

4. In a profiling-machine, the combination, substantially as set forth, of a series of universal bearings, a rod journaled in each of 105 said bearings, a blank-chuck upon one end of each of said rods, a bar pivoted to all of said rods and holding them parallel, a chuck-rod in prolongation of one of said rods, a templet-chuck carried by said chuck-rod, a guide-pin rigidly supported by said bed and presenting 110 its end to said templet-chuck, a head-block mounted for sliding motion on the bed to and from said blank-chucks, a screw for adjusting said head-block on the bed, a series of head-blocks fitted to slide in said head-block 115 to and from said blank-chucks, screws for adjusting said head-blocks in said head-blocks, and a cutter-arbor journaled in each of said head-blocks.
